UNITED STATES PATENT OFFICE.

WILLIAM F. WAINRIGHT, OF WINCHESTER, ILLINOIS.

GRADER.

1,111,420.

Specification of Letters Patent.

Patented Sept. 22, 1914.

Application filed March 19, 1914. Serial No. 825,889.

To all whom it may concern:

Be it known that I, WILLIAM F. WAINRIGHT, a citizen of the United States, residing at Winchester, in the county of Scott and State of Illinois, have invented a new and useful Grader, of which the following is a specification.

This invention relates to grading machines particularly designed for use in road building, one of the objects of the invention being to provide a simple and durable structure of this character having means whereby it can be kept in line while being drawn forward.

Another object is to provide a grader the scraping member of which can be adjusted angularly relative to the main beam whereby the area covered by the machine can be narrowed or widened as desired.

A further object is to provide a grading machine which is reversible so that the machine can be drawn back and forth along one side of a road so as to properly crown or build up the road during each trip back and forth along one side of the road, thus saving the time which has heretofore been wasted in taking the machine back to the starting point each time it has been necessary to grade one side of a road several times in succession.

A further object is to provide a grading machine having scraping blades adjustable relative to each other and which can be shifted out of active position so as to enable the carrying beam on which they are mounted to come into contact with the ground and smooth the surface.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of a grading machine constructed in accordance with the present invention. Fig. 2 is a side elevation thereof. Fig. 3 is an elevation showing the opposite side of the machine. Fig. 4 is a section on line A—B

Fig. 1. Fig. 5 is a section on line C—D
Fig. 1.

Referring to the figures by characters of reference 1 designates the main beam of the grading machine, the same being provided at its front end with a forwardly extending tongue 2 to which is connected a clevis 3. A bracket 4 is attached to one side of the rear end portion of beam 1 and journaled within this bracket is a disk 5 adapted to cut into the soil and thus prevent the rear end portion of the beam from swinging laterally out of line during the forward movement of the machine.

Secured to the inner side of the beam 1 at its front end is a hinged member 6 to which is hingedly connected the front end portion of an adjustable beam 7 converging rearwardly from the beam 1 and provided at intervals with inwardly extending brackets 8 to which are pivotally connected arms 9. Additional brackets 10 are secured to the inner side of the beam 1 and have arms 11 pivotally connected to them. These arms 11 lap the arms 9 and each of the arms 9 and 11 is provided, at its free end, with a collar 12. The collar on each arm extends around the opposed arm so that the said arms are thus held against lateral displacement relative to each other although capable of being adjusted longitudinally. Each arm 11 has a bolt 13 extending upwardly therefrom and into one of a series of openings 14 formed in the adjacent arm 9. Thus it will be seen that by removing the bolts 13, the arms 9 and 11 can be adjusted relative to each other after which, by inserting the bolts 13 in the adjacent openings 14, the arms can be held against independent movement. By thus adjusting the arms 9 and 11 the beam 7 is adjusted angularly relative to the beam 1.

Upper and lower pivot bolts 15 are extended laterally from the rear end portion of the beam 7 and pivotally mounted on each of these bolts is the rear end portion of a scraping blade 16. Each blade is substantially equal in width to about one half of the beam 7 and each blade also extends preferably throughout the length of the beam 7. Bolts 17 are carried by each blade 16 and extend through slots 18 formed in the beam 7. Thus it will be seen that by loosening the bolts 17, the blades 16 can be adjusted angularly about the bolts 15 and,

by tightening bolts 17, the said blades will be held against further movement. By adjusting the blades inwardly into contact with each other, their outer or active edges will be brought flush with or slightly past the upper and lower edges respectively of the beam 7, while by adjusting one or both of the blades outwardly, the active edge or edges thereof will be projected beyond the corresponding edges of beam 7 as shown, for example, in Figs. 2 and 3.

When it is desired to build up or crown one side of a road, the disk 5 is placed in engagement with the road at one side thereof and the beam 7 is adjusted angularly to beam 1 until it covers about one half the width of the road. The lower scraper blade is then adjusted downwardly so as to project beyond beam 7 after which the machine is drawn forward. The scraper blade will obviously engage the soil and deflect it laterally toward the center of the road. If, after a stretch of road has thus been treated, it is found that it is desirable to move the scraper again over the same stretch, it merely becomes necessary to adjust the other scraping blade outwardly beyond the beam 7 and then to reverse or invert the machine and draw it back along the same side of the road whereupon the action hereinbefore described will be repeated.

It will of course be understood that where both sides of the road need grading, it does not become necessary to invert the machine as the same can be drawn back along the opposite side of the road. Where only one

side of the road requires grading, however, it has been found desirable to employ a reversible machine such as described. After the road has been graded and it becomes desirable to smooth it, the blades 16 can be adjusted together so as not to project beyond the beam 7 after which the machine can be drawn over the road the beam 7 caused to smooth off the surface.

Disk 5 will of course maintain the beam 1 in line under all conditions, thus adding materially to the efficiency of the machine.

What is claimed is:—

A road grading machine including a main beam, a draft device at one end thereof, soil engaging means at the other end for holding the beam against lateral displacement, a beam hingedly connected to the front end of the main beam and adjustable angularly relative thereto, superimposed scraping blades pivotally connected at their rear ends to the rear end portion of the adjustable beam and adjustable angularly upwardly and downwardly to project their outer edges into or out of active positions said beam constituting a drag when the blades are out of active position, said grading machine being invertible to bring either of the blades into engagement with the soil.

In testimony that I claim the foregoing as my own, I have hereunto affixed my signature in the presence of two witnesses.

WILLIAM F. WAINRIGHT.
